The present design is a rake; the present design is a rake that has an iron plate with a blade in one direction to the middle part of the rake's foot; when a forest fire occurs, the rake pulls the fallen leaves and then pulls to the soil, which is used for extinguishing forest fires, cleaning up residual fires, building defense lines for forest fires, and removing weeds on weekend farms; as shown in fig. 1.9, the length of the handle can be adjusted as needed.
